[57] CLAIM

The ornamental design for a hull for a pontoon-type boat, as shown and described.

DESCRIPTION

FIG. 1 is a bottom plan view of a hull showing our new design, the top plan view being an inside-out image of that shown;

FIG. 2 is a left side elevational view thereof, the right side elevational view being a mirror image of that shown;

FIG. 3 is a front elevational view thereof;

FIG. 4 is a view taken along line 4—4 in FIG. 3; and, FIG. 5 is a rear elevational view thereof.
